UNITED STATES PATENT OFFICE.

JOHN ELLWOOD LEE, OF CONSHOHOCKEN, PENNSYLVANIA, ASSIGNOR TO
JOHNSON AND JOHNSON, OF NEW BRUNSWICK, NEW JERSEY, A COR-
PORATION OF NEW JERSEY.

HOLDER FOR LIQUID SOAP.

No. 847,014.

Specification of Letters Patent.

Patented March 12, 1907.

Application filed January 27, 1906. Serial No. 298,246.

To all whom it may concern:

Be it known that I, JOHN ELLWOOD LEE, a citizen of the United States of America, residing in Conshohocken, in the county of 5 Montgomery, in the State of Pennsylvania, have invented an Improved Holder for Liquid Soap, &c., of which the following is a specification.

The object of my invention is to provide a 10 convenient and simple holder for dispensing liquid soap and the like, and this object I attain by the construction which I will now describe.

In the accompanying drawings, Figure 1 is 15 a vertical section through my improved holder, and Fig. 2 is a side view of a closing-cap which may be used.

The device is mounted in any suitable way 20 on a side wall or other support, and in the drawing I have indicated it as supported by a bracket B, secured at b to one of the usual upright marble slabs or other wall-piece A. The outer end of this bracket B has a screw-threaded ring B' to receive the screw-threaded neck d of a receiver D. To the lower end 25 of this neck of the receiver is secured, as by threading, a cap or stopper E, with a discharge-outlet closed by a suitable valve or cock F.

The receiver D is contracted at the neck d, 30 but has a widened body part above, constituting an upper chamber adapted to hold liquid, or, in other words, it is somewhat in the shape of a bottle standing upside down, and it is open at its upper or widened end, so that 35 an ordinary bottle containing liquid soap, for example, may be introduced upside down in the receiver D and be supported upon the shoulders d' d', formed between the neck and body of the receiver, while the neck of the bottle 40 will be received into the neck of the receiver. The liquid soap there running out into the neck of the receiver will form a seal with the neck of the bottle, as indicated in

the drawing. When the seal is broken by the drawing off of the liquid on opening the 45 valve below, a little more will run out of the bottle into the receiver. When the supply is exhausted, it can be readily, quickly, and simply renewed by replacing the empty bottle by a full one, after taking the cork out of 50 the bottle, of course. On the other hand, should a user not care to recharge his receiver in the quick and simple way I have described, but desires to pour the liquid soap or other liquid into the receiver D, that may be done, 55 and in such case the metal screw-cap E', Fig. 2, will thereupon be secured onto the threaded top e of the receiver to close it.

I claim as my invention—

1. The herein-described holder for dispensing liquid soap and the like, and consisting of a receiver having a neck with a valved closure at its lower end, a widened body part at its upper end open at the top and intermediate shoulders adapted to receive and support a bottle upside down, the widened part above the shoulders constituting a chamber adapted to hold liquid.

2. The herein-described holder for dispensing liquid soap and the like, and consisting of a receiver having a neck with a valved closure at its lower end, a widened body part at its upper end open at the top and intermediate shoulders adapted to receive and support a bottle upside down, the widened 75 part above the shoulders constituting a chamber adapted to hold liquid, and a removable cap for the open upper end of the body of the receiver.

In testimony whereof I have signed my 80 name to this specification in the presence of two subscribing witnesses.

JOHN ELLWOOD LEE.
